UNITED STATES PATENT OFFICE.

WILLIAM J. NESBITT, OF LOS ANGELES, CALIFORNIA.

HEEL-CUTTING APPARATUS.

1,282,456.

Specification of Letters Patent. Patented Oct. 22, 1918.

Application filed October 3, 1917. Serial No. 194,629.

To all whom it may concern:

Be it known that I, WILLIAM J. NESBITT, a citizen of the United States of America, residing at Los Angeles, county of Los Angeles, State of California, have invented a certain new and useful Heel-Cutting Apparatus; and I do hereby declare the following to be a full, clear, and exact description of the invention, such as will enable others skilled in the art to which it appertains to make and use the same.

This invention relates to improvements in heel cutting apparatus; and it may be said to consist in the provision of the novel and advantageous features and in the novel and improved construction, arrangement, and combination of parts as will appear from the description and claims which follow hereinafter.

One object of the invention is to provide a novel and improved construction whereby the heel holding device is adjustable relatively to the cutting device.

Another object of the invention is to provide a novel and improved heel holding device.

A further object of the invention is to provide a novel and improved heel cutting device.

A further object of the invention is to provide a novel and improved heel cutting apparatus which is simple and compact in design, economical to manufacture, install, and operate, practical and convenient to use, and generally effective for its purpose.

Other objects and the advantages of the invention will be apparent to those skilled in the art from a careful consideration of the following description of the preferred construction embodying the invention, taken in connection with the accompanying drawings in which

Figure 1 is a side elevational view of the heel cutting apparatus; Fig. 2 is a plan view of the same; Fig. 3 is a plan view of the frame; Fig. 4 is a sectional view taken on the line 4-4 of Fig. 1; Fig. 5 is side elevational view of the heel cutting device; Fig. 6 is a front elevational view of the same; Fig. 7 is an enlarged sectional view taken on the line 7-7 of Fig. 5; Fig. 8 is an enlarged broken sectional view showing the heel cutting device and a partly cut heel; Fig. 9 shows plan and elevational views of the arm which carries the shoe holding device; and

Fig. 10 shows elevational and plan views of a part of the heel holding device.

The frame 11 has on its underside a suitable stem 12 whereby it can be readily attached to a suitable pedestal 13 which is 60 partly indicated by dotted lines in Fig. 1. Said frame 11 has at its forward end the bearings 14 and 15, and it has at its rear end the upright extension 16 and the toothed part 17. 65

A bifurcated lever 18 is provided with the bearings 19 and 20; and said lever has at its upper end the handle 21, and it has at its lower end the pivots 22 and 23 which are fitted in the bearings 14 and 15. 70

The heel cutting device consists of the circular saw 24 and the thrust finger 25 which are both mounted on the lever 18. The circular saw 24 is fitted on the squared portion 26 of the shaft 27 which latter has fast 75 thereon the sprocket pinion 28 and is fitted in the bearing 19. A reduced portion 29 of the shaft 27 has thereon the sleeve 30 which is fitted in the bearing 20 and jammed against the circular saw 24 by the lock nut 80 31. Washers 32 and 33 are placed between the circular saw 24 and the bearings 19 and 20, and a washer 34 is placed between the sleeve 30 and the nut 31. The bearing 19 has thereon a projection 35 provided with 85 an opening in which is adjustably fitted the offset stem 36 which is provided at the inner end of the thrust finger 25 and is locked in the adjusted position by the set screw 37. The thrust finger 25 has an outward in- 90 clination toward the circular saw 24 and it has its outer edge 38 beveled and normally spaced slightly from the outer edge portion 39 of the circular saw 24.

As shown in this instance the shaft 27 95 is driven by the sprocket chain 40 which is in contact with the sprocket pinion 28 and the sprocket pinion 41 which latter is suitably mounted on one end of the arm 42 which has its other end pivotally mounted 100 at the upper end of the extension 16. The arm 42 normally bears against the stop 43.

The shoe holding device consists of the plates 44 and 45 which are formed and arranged to provide a recess which is inclined 105 forwardly and upwardly and adapted to receive the heel 46 of a shoe 47; said plates 44 and 45 having beveled edges 48 and 49 which are adapted to fit in the crease between the heel seat and the heel of the shoe. The bev- 110

beveled edge 48 fits in the crease around the rear end part of the heel 46 and at the forward end of one side of the heel, and the beveled edge 49 fits in the crease at the forward part 5 of the other side of the heel. The plate 44 is suitably attached to the upright extension 50 on one end of the table 51 which has a handle 52 at its other end, and the plate 45 is suitably attached to the lever 53 which has a handle 54 at its upper end and has its lower end mounted on the pivot 55 on the upright extension 50 of the table 51.

In order to adjust the heel holding device relatively to the circular saw 24, the table 15 51 is pivotally mounted on the arm 56 which has a handle 57 at its forward end and has its rear end pivotally mounted on the frame 11. The table 51 extends substantially at a right angle to the circular saw 24, and the 20 arm 56 is disposed substantially parallel to said circular saw. A pivot 58 passes through the table 51 and the arm 56, and said pivot passes through a spring 59 which is interposed between the arm 56 and a nut 60 on the pivot so that the table 51 makes close contact with the arm 56. The table 51 is provided on its underside with teeth 61 which are adapted to fit in the notches 62 provided in the upper part of the arm 56 to 25 positively hold the table 51 in adjusted position when it is turned on the pivot 58. A pivot 63 passes through the rear part of the arm 56 and the part 17 of the frame 11, and said pivot passes through a spring 64 which is interposed between the part 17 and a nut 65 on the pivot so that the arm 56 is held in close contact with the part 17. The teeth 66 on the part 17 are adapted to fit in the notches 67 in the underside of the arm 56 to 30 positively hold the arm 56 in adjusted position when it is turned on the pivot 63.

From the foregoing, the construction, manner of use, and the advantages of the improved heel cutting apparatus will be understood by those skilled in the art. The 45 shoe 47 is placed to have the beveled edge 48 disposed in the crease between the heel seat and the heel 46, and then the lever 53 is moved to have the beveled edge 49 disposed 50 in the crease and hold the shoe so that a part of the heel can be cut off. It will be seen that the form and arrangement of the plates 44 and 45 permit the operator to easily and quickly place the shoe and clamp it in the 55 holder. The arm 56 can be turned toward the circular saw 24 according to the amount that it is desired to cut off of the heel; and then the table 51 can be turned to adjust the shoe holding device so that either a straight 60 cut or an angular cut longitudinally of the heel can be made as may be desired. In order to do effective work in cutting the leather and

nails of the heel 46, the circular saw 24 must be comparatively thin. When a comparatively thin circular saw is used to cut the 65 heel it does not cut in a straight line because the intact part 68 of the heel 46 presents a greater pressure or thrust against the circular saw 24 than does the slice 69 which is being cut off of the heel. The finger 25 prevents the circular saw 24 from being thrust away from the intact part 68 and causes the circular saw 24 to make a straight cut through the heel 46.

The construction which has been particularly illustrated and described admits of minor changes and modifications—wherefore the right is reserved to all such changes and modifications as do not depart from the spirit and scope of the invention which is defined in the appended claims.

I claim:

1. Heel cutting apparatus comprising the combination of a frame, a cutter, an arm extending substantially parallel to the cutter 85 and having its rear end part pivotally connected to the frame, a table extending substantially at a right angle to said arm and pivotally connected to said arm, and a shoe holding device on said table.

2. In heel cutting apparatus, the combination of a lever, a circular saw rotatably mounted on said lever, and a thrust finger having its inner end connected to said lever and having its outer edge beveled and normally spaced slightly from the outer edge portion of the circular saw, said thrust finger having an outward inclination toward the circular saw, substantially as set forth.

3. In heel cutting apparatus, the combination of a lever, a circular saw rotatably mounted on said lever, and a thrust finger having its inner end connected to said lever and being inclined toward the outer edge portion of the circular saw.

4. The herein-described shoe holding device consisting of plates formed and arranged to provide a recess which is inclined forwardly and upwardly and adapted to receive the heel of a shoe, said plates having beveled edges which fit in the crease between the heel seat and the heel of the shoe, one of said plates being adapted to fit in the crease around the rear end part of the heel and at the forward end of one side of the heel, and the other plate being adapted to fit in the crease at the forward part of the other side of the heel, and a pivoted lever to which the last mentioned plate is connected.

In testimony whereof, I have signed my 120 name to this specification at Los Angeles, county of Los Angeles, State of California, this 24th day of September A. D. 1917.

WILLIAM J. NESBITT.
